L. BRUNETTE,
 AUTOMATIC RELEASE MECHANISM FOR VESTIBULE CURTAINS,
 APPLICATION FILED JUNE 30, 1919.
1,323,007. Patented Nov. 25, 1919.
 2 SHEETS—SHEET 2.

UNITED STATES PATENT OFFICE.

LOUIS BRUNETTE, OF QUEBEC, QUEBEC, CANADA, ASSIGNOR OF ONE-HALF TO FRANK HARRINGTON FRENCH.

AUTOMATIC RELEASE MECHANISM FOR VESTIBULE-CURTAINS.

1,323,007.

Specification of Letters Patent.

Patented Nov. 25, 1919.

Application filed June 30, 1919. Serial No. 307,627.

To all whom it may concern:

Be it known that I, LOUIS BRUNETTE, a subject of the King of Great Britain, residing at Quebec, Province of Quebec, Canada, 5 have invented certain new and useful Improvements in Automatic Release Mechanism for Vestibule-Curtains; and I do hereby declare that the following is a full, clear, and exact description of the invention, such 10 as will enable others skilled in the art to which it appertains to make and use the same.

This invention relates to automatic release mechanism for vestibule curtains and the 15 principal object is to produce a simple and reliable mechanism for automatically holding and disconnecting the free ends of car vestibule curtains, whenever the car to which they are attached are drawn apart, 20 thus preventing injury to the curtains and permitting them to roll up automatically out of the way.

A further object of the invention is to provide a fastening device, which will normally hold the curtain in its extended position across the diaphragm, but which will yield when unusual strain is imposed upon the curtain and thus release the curtain before it is injured.

30 Another object of the invention is to release the curtains simultaneously with the parting of the air couplings.

A still further object of the invention is to provide for the release of the curtains by 35 electrical means and obviating the use of pneumatic means.

With the above and other objects in view which will hereinafter appear as the description continues, the invention consists of the 40 novel features of construction, combination and formation of parts as will be hereinafter more fully described and particularly pointed out in the appended claims.

In the accompanying drawings has been 45 shown a simple and preferred form of the invention, it being, however, understood that no limitation is necessarily made to the precise structural details herein exhibited, but the right is hereby reserved to any changes, 50 alterations or modifications to which recourse may be had that come within the scope of the claims without departing from

the spirit of the invention or sacrificing the efficiency of the same.

In the accompanying drawings:

Figure 1 is a rear elevational view of the device;

Fig. 2 is a longitudinal section with the plunger and the locking wheel in elevation; 60 and,

Fig. 3 is a detail sectional view, illustrating the locking mechanism in plan elevation.

Fig. 4 is a detail view of a modified form of locking mechanism in a casing with cover removed;

Fig. 5 is a side elevation of the same with the casing in section;

Fig. 6 is a horizontal section on line 6—6 of Fig. 5;

Fig. 7 is a perspective view of the winding 70 drum, switch and release members, illustrating the cord and electrical connections;

Fig. 8 is a sectional view of the switch member;

Fig. 9 is a detail sectional view of the winding drum and casing; and,

Fig. 10 is a horizontal section on line 10—10 of Fig. 9.

Referring now more particularly to the accompanying drawings wherein like and 80 corresponding parts are designated by similar reference characters throughout the several views.

The numeral 1 indicates a portion of the vestibule of a car, which is connected to another car in the usual manner by draw bars and hose of the air brake system, not illustrated. Each car is provided with the usual vestibule diaphragm, which are adapted to be covered by a curtain 2, so that passengers 85 passing from one car to the other, will not come in contact with the vestibule diaphragms. The curtains 2 are mounted upon the usual spring actuated rollers, which latter are supported upon the vertical beams 90 of the vestibule of the opposite cars and the free ends of the curtains are provided with loops 3, which are adapted to be connected to a locking element.

The foregoing is the well known construction and used upon many of the railway coaches, and it has been found that these curtains are often torn or broken, due to the fact that they are not released when the air

and draw bar couplings are disconnected. Therefore, it is the purpose of the present invention to provide means for automatically releasing the curtains 2, whereby the 5 same may be rolled up when the cars are being uncoupled.

Formed within the vertical vestibule bar 1, is a recess 4 and mounted in this recess and carried by a front housing plate 5, is a 10 housing 6, formed at its lower end with a bracket 7. A pin 8 is mounted in said bracket 7 and has its lower end journaled in the lower plate 9 of the housing. Pivotally mounted on said pin 8 is a locking wheel 15 10, and the latter is provided with four hooked projections 11, which are adapted to engage the loops 3 of the curtain 2, so as to hold the latter in its opened position. The rear faces of each of the hooked projections 11, are flattened as at 12 and the body portion of the wheel 10, between the flattened portions 12 and the hooks 11 is formed with arcuate recesses or seats 13.

The housing 6, is formed with a hollow 25 cylinder 14, which extends downwardly from the top housing plate 15 and is spaced from the inner surface of the front housing plate 5. The lower end of the cylinder 14, is exteriorly screw threaded at 16, for 30 the reception of an interiorly threaded cap 17, which forms the closure for the open end of the cylinder.

A plunger is adapted for vertical movement within the cylinder 14 and carries the 35 usual head 18 and rod 19. The head 18 carries the usual gaskets 20 secured thereto by means of a screw 21 and a coil spring 22 encircles the said rod 19 and engages one of the gaskets 20 and the inner face of cap 17, 40 serving to normally tension the said plunger head 18 toward the upper end of the cylinder. The lower end of the plunger rod 19 projects downwardly through an opening in the cap 17 and the said plunger is actuated 45 by air, which enters cylinder 14, through a pipe 23, leading from the train air supply. The air under compression will impinge against the head 18 of the plunger and force the same downwardly to position the rod 50 19, so that it will be engaged by one of the hooked projections 11, of the locking wheel 10 and be disposed in one of the arcuate recesses or seats 13, thereby holding the said wheel 10 against revolution.

55 Should the cars be parted, the air couplings would be uncoupled, which breaks the air supply line and resultant of this operation, the air pressure on the plunger head 18, would cease and spring 22, would 60 turn the plunger to normal position, thereby raising the plunger rod 19 from engagement with the locking wheel 10. As the curtains are attached to said wheels, upon the release of the latter by the withdrawal 65 of the plunger rod 19, the said wheels are

allowed to revolve and consequently the looped ends 3 of the curtains become disengaged from the hooked projection 11, to which they may be attached. From this it is evident that when the cars have been uncoupled the hose couplings will be severed, thereby releasing the curtain and permitting the same to be wound upon the roller and out of the way, so as to prevent the curtain from being torn or broken when the 70 cars have been accidentally uncoupled. Carried by plate 5 is a bracket 24 and the latter has pivotally mounted therein a guard 25, so as to prevent persons passing from one 75 car to another coming in contact with any 80 of the hooks. One end of this guard 25 rests against the coil spring 26, which normally holds the guard in the position illustrated in Fig. 3, and this flexible mounting of the guard permits the loop 3 of the curtain to readily pass under its free end when connecting the same to the hooked projections 11, and likewise providing for the ready disengagement of the same, when the 85 cars are uncoupled.

In the modified form of my device, I dispense with the air coupling and release mechanism and provide an electrical equipment which will be described as follows:

A drum 27 is mounted in a casing 28, 90 which latter is secured in any appropriate manner to the under frame of one car and said drum is revolvable on a stem 29, around which is disposed a coil spring 30, one end of which is attached to a pin 31 on the said drum. A cable 32 is wound around the drum 27 and its free end is attached to a fiber plug 33. The plug 33 is adapted for location within the switch casing 34, secured to the under frame of the adjoining 100 car and said plug 33 is formed with a concaved channel 35. A plate 36 of some good conductive material has one end secured to a plug 37, and a screw terminal 38 is passed through switch casing 34 and engages the 105 plug 37. A wire 39 leads to the battery 40. The plate 36 is formed at its medial part with a lug 41, which is normally disposed in the concaved channel 35 of the plug and said plate is likewise formed with a contact 110 lug 42, which is normally out of engagement with a similar contact lug 43 on the plate 44, which is secured within the switch casing 34. A terminal 35 is connected to plate 44 and a wire 45 attached thereto, 115 leads a post 46 of solenoid 47. The other post 48 of the solenoid is connected to the battery 40 by a lead wire 49, thus completing the circuit from the switch to the solenoid. The solenoid 47 is mounted in casing 120 50 and the core 51, of the latter carries on its lower end a beveled plate 52.

An armature plate 53 is hingedly mounted in a lug 54 in the casing 50 and is disposed below the solenoid plate 52.

A wheel 55 is pivotally mounted on pin 56 in said casing 50 and the latter is provided with four hooked projections 57, adapted to engage the loops 58 of the curtain, so as to hold the same in its opened position.

The plate 53 on its lower surface is provided with a trip lug 59, adapted for normal engagement with one of the hooked 10 projections 57 of the wheel 55, to hold the same against revolution.

In operation, should the coupling connection between the cars be severed, the plug 33, would be withdrawn from the switch 15 casing 34 and the end of the plug would engage the lug 41, on plate 36, thus elevating the end of said plate and causing the lug 42 thereon to contact lug 43 on plate 44, thus closing the circuit to the solenoid 47. 20 The solenoid being thus magnetized, energizes plate 53 and draws the same into contact with the plate 52, elevating the lug 59 from engagement with the wheel 55, so that 25 the latter is released and allowed to revolve to disengage the curtain loop 58 from one of the hooks 57.

When the connection is made again, the plug 33 is merely inserted within the switch 30 casing 34 and the plate 53 is normally held in locking position with the wheel 55 by a spring 60.

Whereas I have shown means for automatically releasing the curtains and which means have been pneumatically operated, it 35 is of course to be understood that an electrical or other mechanical equipment may be used for operating the same that come within the scope of the appended claims.

Having thus fully described my invention, what I claim as new and desire to secure by Letters Patent is:—

1. The combination with a tension op-

erated curtain, of a housing, a cylinder formed integral with said housing, a plunger slidable in said cylinder, an air 45 supply pipe connected to said cylinder, a cap adjustable on said cylinder, a spring arranged in said cylinder for normally tensioning said plunger toward the upper end thereof, a locking wheel pivotally mounted 50 in said housing and comprising a plurality of hooked projections, the said curtain adapted for connection to one of said hooked projections, and the said plunger adapted to be actuated by air pressure to move the 55 same downwardly into engagement with another of said hooked projections for holding said locking wheel against revolution.

2. The combination with a tension operated curtain, of a housing, a cylinder 60 formed integral with said housing, a plunger slidable in said cylinder, an air supply pipe connected to said cylinder, a cap adjustable on said cylinder, a spring arranged in said cylinder for normally tensioning said plunger toward the upper end thereof, a locking wheel pivotally mounted in said housing and comprising a plurality of hooked projections, the said curtain adapted for connection to one of said hooked 65 projections, the said plunger adapted to be actuated by air pressure to move the same downwardly into engagement with another of said hooked projections for holding said locking wheel against revolution, and a 70 guard carried by said housing inclosing a portion of said locking wheel.

In witness whereof I have hereunto set my hand.

LOUIS BRUNETTE.
